GARMENT CUTTING MACHINE

Solomon Sheer, Brooklyn, and Victor Ginsburg, Jackson Heights, N. Y., assignors to Tex Machine Corporation, New York, N. Y., a corporation of New York

Application September 11, 1941, Serial No. 410,366

11 Claims. (Cl. 164—71)

1

This invention relates to an apparatus for trimming the nether edge of feminine garments, such as dresses, skirts and the like.

The primary and general object of our invention is the provision of a highly improved apparatus of the character described which may be employed on garments of all types and materials. It is a more particular object of my invention to provide a device which will consistently trim garments to a substantially straight edge in the shortest possible time and with a minimum of effort.

Certain objects of our invention relate to the dress cutting and handling apparatus and are to provide a mechanism of this character which may be manipulated by unskilled labor, which is completely power driven, which requires no initial manipulation on the part of the operator other than moving of a starting lever, which automatically feeds fabric to the cutter at the proper rate for trimming along a substantially straight edge, and which automatically maintains keen cutting edges.

Another object of our invention is to provide improved apparatus for disposing a garment in proper relationship to the cutter. In this connection, it is more particularly an object of my invention to permit the use of readily interchangeable garment forms, to facilitate the adjustment of the garment neckline relative to the cutter and to prevent this adjustment from being unintentionally disturbed.

A further object of our invention is to provide a garment trimming machine which is rugged in construction, simple and reliable in operation, and highly efficient for the purposes set forth.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawings, in which is shown one of the various possible embodiments of this invention,

Fig. 1 is a front elevational view in partial section of a garment trimming machine embodying my invention, with the various elements thereof arranged in inoperative position;

Figs. 2 and 3 are sectional views taken along the lines 2—2 and 3—3 respectively of Fig. 1;

2

Fig. 4 is a sectional view taken along the line 4—4 of Fig. 2;

Fig. 5 is a sectional view taken along the line 5—5 of Fig. 2, but illustrating the various parts thereof in operative position;

Fig. 6 is a sectional view taken along the line 6—6 of Fig. 5;

Fig. 7 is an enlarged sectional view of the cutting blades taken substantially along the line 7—7 of Fig. 5;

Fig. 8 is a sectional view taken along the line 8—8 of Fig. 7, being explanatory of the means employed to automatically maintain the cutting blades sharpened; and

Fig. 9 is an enlarged sectional view taken along the line 9—9 of Fig. 6, showing in detail the mechanism employed to set the length of the trimmed dress and to permit the use of interchangeable garment forms.

Generally we accomplish the foregoing objects of our invention by providing a rotating garment form and a pair of rotating cutter blades, all of which are turned by power about fixed axes. In this manner, we avoid movement of the cutter around the dress and can so arrange our apparatus that the cutting and control stations occupy a fixed position which can be disposed so as to be most conducive to efficient operation. Also, in order to insure trimming the garment along a straight edge, regardless of the type of garment being trimmed or the nature of the fabric from which the garment is made, we provide a flexible feeding mechanism which bunches up the dress material and automatically feeds it to and past the cutter blades at the same angular speed at which the garment is turned.

Referring now to the drawings, 10 denotes a garment trimming machine embodying our invention and basically comprising a source of power A, a revolvable garment supporting means B, a pair of revolvable cutters C which can be moved towards and away from an operative position where their axes are fixed relative to the dress holding means, a fabric feeding mechanism D which is also adapted to be moved towards and away from operative position, and a control E which, upon actuation, simultaneously renders the dress holding means, the cutter blades and the feeding means operative and disposes the cutter and feeding means in operative position.

The source of power A comprises a motor M (see Figs. 3 and 5) supported on a hollow base 11. Said motor may be of the type having an internal reduction drive housed in an end casting 12 and from which extends a vertical drive

shaft 13 carrying a pinion gear 14. The gear 14 meshes with a large spur gear 15 mounted on a shaft 16 from which all of the several rotating parts are driven. Said shaft 16 is suitably journaled in the top wall of the base 11 and has fixed thereon a gear 17 and sheave 18 for actuating the fabric feeding mechanism D and garment supporting means B respectively. The several gears disposed on the top of the base 11 may be covered by a casing member 19 which is held by screws 20 to the said pedestal.

Since, as will be seen from Fig. 1, the garment supporting means B and associated structure are quite large and disposed to one side of the base 11, we prefer to employ a pair of spread legs 21 to stabilize the trimming machine 10 and prevent same from toppling over if inadvertently jostled.

The garment supporting means B, in accordance with our invention, is so constructed and arranged that it will revolve about a fixed axis which may be denoted as the point 22 (see Fig. 2). For this purpose, the garment supporting means may comprise a hollow steel shaft 23 (Fig. 5) which is journaled in a vertically disposed bearing 24 integral with the base 11. To prevent vertical displacement of said shaft 23, we bolt to the top wall of the bearing 24 a step bearing 25 which rotatably supports a collar 26 held by a set screw 27 (Fig. 1) to the shaft 23. At the lower end of the shaft 23 we mount for rotation therewith a large sheave 28 whose upper surface is disposed in sliding contact with the lower face of the bearing 24. Power for rotating the shaft 23 is supplied by a cable 29 interconnecting the sheaves 28 and 18.

Fixed by a bolt 30 to the upper end of the shaft 23 for rotation therewith is a fitting 31 (see Figs. 5, 6 and 9) which is adapted to regulate the vertical position of the garment supporting means so as to vary the distance between the neckline of a garment and the cutters C. Said fitting comprises a vertical barrel 32 which is telescopically received on the upper end of the shaft 23. Integrally formed with said barrel is a horizontal barrel 33 whose longitudinal axis is slightly offset with respect to the longitudinal axis of the barrel 32. The barrel 33 has fitted therein a bushing 34 in which is journaled the enlarged portion 35 of a crank shaft 36. Adjacent said enlarged portion 35 is a pinion 37 which is disposed partially within the barrel 33 and partially within the barrel 32 where it meshes with a long rack gear 38 formed in one face of an elongated vertical measuring rod 39 slidably received in the shaft 23.

In order to provide sufficient bearing support for the gear 37 which normally carries an appreciable weight, including the measuring rod 39 and form 40 on which a garment G may be draped, we form an extension 41 on the shaft 36 disposed on the opposite side of the gear 37 from the enlarged portion 35, said extension being received in a bearing portion 42 cast integrally with the barrels 32 and 33. The free end of the shaft 36 is of non-circular sectional contour, for example of square shape as shown in Fig. 6, so as to slidably receive the socket of a crank 43 (Fig. 1) which can thus be employed to raise or lower the measuring rod 39 and form 40. The form 40 is held in any adjusted position by clamping means, such as a long threaded rod 44 received in a tapped horizontal barrel 45 whose axis transects and is substantially coplanar with the axis of the barrel 33.

Suitable markings N are provided along one of the faces of the measuring rod 39, which cooperate with a pointer (hereinafter described) to indicate the distance between the neckline of the garment G and the cutters C in any adjusted position. If desired, additional markings N' may be provided on another face of the rod for cooperation with another pointer to indicate the distance between the waist line of a skirt and the cutters.

Means may also be provided to connect the form 40 to the vertically adjustable rod 39 in such manner as to allow ready interchangeability of forms and to cause rotation of the form with the rod. To this end, the top portion of the rod 39 is rounded into a cylindrical pillar 46 (Fig. 9) whose upper end is tapered, as indicated at 47. Pinned to the base of the pillar is a large disc 48 which is recessed at 49 to form an annular raised surface 50. A similar raised surface 51, provided on a disc 52 which is attached to the undersurface of the form 40, cooperates with the surface 50 to create a friction slip drive between the rod 39 and form 40. Extending upwardly from the central portion of the disc 52 is a vertically disposed open-ended tubular member 53 which snugly receives the circular pillar 46. The lower end 54 of the tube 53 is preferably flared out, as shown in Fig. 5, to facilitate mounting of the said form upon the measuring rod.

Also fixed to the shaft 23 for revolution therewith is a cutting rest 55 which is adapted to cooperate with the fabric feeding means D during the cutting operation. Said rest 55 may be in the form of a short cylinder fabricated from light gauge metal and connected by a plurality of spider arms 56 to a hub 57 on the shaft 23 between the fitting 31 and a collar 58. A key 57a rotates the hub 57 with the shaft 23.

The diameter of the rest 55 should be at least substantially equal to the maximum dimension of the lower portion of the garment holding form 40, and in the form of our invention herein described we have shown said rest as being of a diameter but slightly larger than the width of the said form. If the machine is to be used wholly to trim garments which are very full in the skirt portion, a rest having a larger diameter may be employed. However, it will be seen as the description proceeds that our novel garment trimming machine will trim the skirt portion along a substantially straight line regardless of the fullness of the skirt.

The top of the rest is covered in any suitable manner, as by a plurality of integral conical sections 59 and 60 which conceal the fitting 31 and prevent dust or fabric scraps from interfering with the vertical adjusting action. One of the sections 59 has holes 61 and 62 to permit the shafts 36 and 44 to extend externally of the said cover to a position where they may be readily manipulated. Pointers 63 and 64 are marked on the surface of the section 60 for cooperation with the measuring numerals N and N'.

The cutters C are preferably constructed, according to our invention, so that they are disposed in non-operative position relative to the garment at all times save during actual trimming, and thus permit free manipulation of the garment G on the form 40 before the garment is rotated during trimming. Said cutters are also so designed that they will sever a plurality of layers of the heaviest fabric likely to be employed in a dress or coat as soon as the fabric comes into contact with the cutters and with-

out causing any fabric to back up in front of the blades.

The cutters C may comprise a pair of circular cutting discs 65 and 66 carried in a housing 67. Said discs are mounted so as to be constantly disposed in cutting relationship to each other, the lower blade 66 being beveled downwardly and the upper blade 65 being beveled upwardly.

Means is provided to enable the blades to be simultaneously vertically moved toward and away from the horizontal plane wherein cutting is performed. Such means comprises a shaft 68 (Fig. 5) on which the upper cutting blade 65 is fixedly mounted. The said shaft 68 is journaled in a vertical bearing 69 forming part of the cutter casing 67, and extends below the bearing to the pedestal 11 where the lower end of the shaft is received in another journal 70. A gear 71, in mesh with the gear 15, is provided on the shaft 68 adjacent the bearing 69, said gear 71 having an elongated slot therethrough which slidably receives a key 72 disposed longitudinally of the shaft 68. The shaft 68 is maintained in fixed position relative to the cutter housing 67 by a bevel gear 73 which is pinned to the shaft immediately below the bearing 69, the upper surface of said bevel gear being disposed in sliding contact with the lower face of said journal. It will be seen, therefore, that when the motor M is actuated, power will be transmitted to rotate the upper cutter blade 65 through the gear 71 and shaft 68, and that the vertical position of the shaft 68 and blade 65 may be varied without disturbing the said driving train.

Power is transmitted to the lower cutter blade 66 through the gear train comprising bevel gear 74, shaft 75 which is journaled in a web depending from the gear housing 67, bevel gear 76, bevel gear 77, and shaft 78 on which the cutter blade 66 is mounted for rotation. For safety and to prevent jamming by fabric scrap, this driving train is concealed in a casing 79 carried by the cutter housing 67.

The cutter blades 65 and 66 and their driving mechanism above described are preferably so arranged that they will automatically maintain a keen cutting edge, and to this end we provide the following construction:

The shaft 68 is disposed vertically while the shaft 78 on which the cutter blade 66 is supported is disposed slightly inclined from the vertical, as best seen in Fig. 8 wherein the angular offset of the said shaft 78 is exaggerated. The lower end of the said shaft 78 extends below the bevel gear 77 which drives the shaft and this extended portion 80 is recessed to provide a socket 81 in which is disposed a compression spring 82. The compression spring forces a ball-bearing 83 against a hardened plate 84 bolted to the lower end of the web in which the axle 78 is journaled. In this manner it will be seen that the axle 78 and cutter blade 66 are constantly urged upwardly under a resilient pressure which causes the blades 65 and 66 to lightly press against each other at a single point of contact O (Fig. 7) where the rubbing of one blade against the other will automatically maintain a sharp cutting edge on both blades.

The bevel gear 77 is mounted on the axle 78 with a sliding key-and-slot connection (shown in Fig. 8) to permit vertical displacement of the axle 78 as the edges of the circular blades wear down.

It is also desirable to provide means to keep the cutting faces of the blades 65 and 66 free from fabric scraps. Such means may comprise a guard wall 85 which surrounds the major portion of the periphery of the cutting blade 66 and which is capped by a cover plate 86. A felt 87 bridges the open sector of the guard wall, said felt being slitted to permit the cutting portion of the blade 66 to project therethrough.

A felt 89 associated with the other cutter blade 65 is mounted directly upon a horizontal web 88 of the cutter casing 67, said felt being in the form of a strip 89 underlying and contacting a major portion of the periphery of the blade 65. The cutting portion of the blade 65 extends beyond the felt 89 and is thus left clear. If desired, conventional oil drips (not shown) may be associated with each of the felts 87 and 89. The cutter blade 65 is provided with a sheet metal guard 85a bolted to the web 88.

The point of contact O between the two blades 65 and 66 at which the cutting takes place should be disposed, when the cutters are in operative position, below and slightly outwardly of the periphery of the cutting rest 55, and we prefer to have the cutters vertically translatable to and away from their point of cutting rather than to have the blades simultaneously move outwardly along a horizontal plane, or to have the blades separated from each other. In this manner, a garment may be readily draped when the cutters are in operative position, yet the cutter blades are permanently maintained in cutting alignment.

Also in accordance with our invention, we provide novel means for feeding the dress fabric to and past the cutters C, said means being so constructed and arranged that it will cause the fabric of dresses of all fullnesses to move past the cutting point O of the cutters C at an angular speed substantially equal to that at which the form 40 is rotated; and in this manner we are able to trim the nether portion of a garment along a substantially straight line. Such means comprises two belts 90 and 91 which respectively serve to gather up the fabric and urge the gathered fabric to and past the cutters C. The belt 90, shown in operative position in Fig. 6, is so disposed as to engage portions of the garment ahead of the cutters C. The linear speed of this belt is greater than the linear speed of the cutter rest 55 and the belt is disposed on an angle thereto so that fabric at the bottom of the dress which comes into contact with the belt 90 is urged towards the belt 91. Thus, if the garment skirt is slightly full, as shown in Fig. 6, while the form 40 is moving the garment G towards the cutter, this slight fullness of the portion of the garment about to be cut is gathered up into folds or corrugations by the belt 90. However, due to the fact that the belt is angularly disposed with respect to the rest 55, the additional material forming the fullness of the remaining portion of the skirt will not be forced towards the cutter. After the garment material leaves the belt 90, it is taken up by the belt 91 which moves at substantially the same linear speed as the rest 55. The belt 91 is so disposed as to lie substantially tangent to or to rest with a light pressure against the rest 55 above the cutting point O. Thus, the goffered or pleated garment material which is fed towards the cutters C by the belt 90 is caused to move past the said cutters at a uniform angular speed by the belt 91. This action results in trimming the dress along a substantially straight line.

To operate the belts 90 and 91 in the manner above described, we provide the following supporting and driving mechanisms:

A shaft 92 is journaled in the base 11 and carries a sheave 93 at the lower end of said shaft extending into the hollow portion of the pedestal. This sheave is connected by a cable 94 to another sheave 95 which is fixed to a shaft on which there is carried a gear 96 meshing with the gear 17 on the power shaft 16. Mounted for rotation with the shaft 92 is a crown pulley 97 on which the belt 91 rides, the belt also being supported on spaced crown pulleys 98 and 100 carry the belt 90. The pulleys 98, 99 and 100 are all supported on a bracket 101 which is rotatably mounted on the shaft 92 and which is maintained in fixed vertical position thereon by a collar 102. Motion is transmitted from the pulley 98 to the pulley 99 by pulleys 103 and 104 mounted for rotation with the pulleys 98 and 99 and interconnected by a cable 105. In order to provide increased speed of travel of the belt 90, the pulley 103 is made larger than the pulley 104. Gathering of the garment fabric may be facilitated by disposing the belt 90 at a lesser angle to the rest 55 than the belt 91.

It will now be seen that after a garment G has been draped on the form 40 and a suitable adjustment made to trim the said garment to a desired length, it is only necessary to cause rotation of the shaft 23, the cutter blades 65 and 66, and the shaft 92 after the said blades and the belts 90 and 91 driven by the shaft 92 are properly positioned. Such action is carried out substantially simultaneously, in accordance with my invention, by manipulation of a single control lever 106. Said lever is pivotally mounted on upstanding leg 107 secured to the pedestal 11 and preferably lined up with the cutting point O so that an operator of the machine may inspect the garment G as it is being trimmed.

Three kinematic linkages which are attached to and actuated by the control lever 106 vertically raise the cutters into operative position, swing the belts 90 and 91 into operative relationship relative to the rest 55 and supply current to the motor M, which, through the drive shaft 16, revolves the form-revolving shaft 23, cutter revolving shaft 68 and the belt-revolving shaft 92.

The linkage which raises the cutters C into position includes an arm 108 fixed to the control lever 106 and having pivotally mounted on its free end a link 109 pivotally attached to the horizontal web 88 of the cutter housing so that upon clockwise rotation of the lever 106, as viewed from Fig. 1, the cutter housing, carrying with it the cutter blades 65 and 66, will be moved upwardly. Rotational or horizontal movement of said housing is prevented by a pair of guide posts 110 and 111 fixed to the base 11 and slidably received in journals 112 and 113 formed in the web 88. Upward and downward motion of the casing 67 is limited by collars 114 and 115 fastened to the guide posts 110 and 111. Since the linkage between the casing 67 and the control lever 106 is positive, the collars 114 and 115 additionally serve to limit the extreme positions of the said control lever. The operative and inoperative positions of the cutters C and their associated linkage are shown in Fig. 1 in dotted and full lines, respectively.

The linkage which swings the frame 101 carrying the belts 90 and 91 comprises an arm 116 integral with the arm 108. A link 117 is connected at one end to the arm 116 by a swivel joint of

any standard construction, as for example the ball-and-socket joint shown in Fig. 6. The other end of the said link 117 is connected by a similar ball-and-socket joint to the frame 101 so that when the lever 106 is disposed in the dotted line position (shown in Fig. 1) the frame 101 together with the belts 90 and 91 will be disposed in operative position as illustrated in Figs. 5 and 6; while when the lever 106 is in the full line position shown in Fig. 1 the frame and belts will be disposed in inoperative position, as illustrated in Figs. 1 and 2.

The kinematic linkage which switches on and off the power for the motor M comprises a clevis fitting 118 pivotally supported on the arm 108 and having a long rod 119 rigidly mounted on its base. This rod is connected by a light spring 122 to the switch arm 120 of a switch 121 in the electric supply circuit of the motor M. The spring 122 comprises a central portion having a full helical turn and two end portions angularly disposed with respect to each other and extending outwardly of the helical central portion. One of these ends is rigidly fixed to the lower end of the rod 119, while the other end of the spring is provided with a hook which is freely received in a small hole at the end of the switch arm 120. By virtue of this construction, when the lever 106 is moved from its off position (full line) towards on position (dotted line), the arm 119 will move almost the full extent of its travel before sufficient force is transmitted through the spring to throw the switch arm 120 and thus the motor M will not be energized until the cutter blades C and fabric feeding mechanism D are disposed substantially in their operative position.

In the operation of our machine a garment G is first draped on the form 40 and its neckline adjusted by manipulation of the crank 43 until it is positioned in such relationship to the cutters C that it will be cut to the desired length indicated by the numerals N. The clamping rod 44 is then tightened and the control lever 106 swung to operative position. This causes the cutters C to rise and shortly before they reach cutting position to rotate. It will be noted that immediately before the cutters C begin to turn the overlying portion of the garment is bunched up over the cutter blades, and said cutters, upon actuation, will slice through this gathered material until they reach the set cutting level. Cutting is continued until the form 40 has rotated sufficiently to re-position the cutters at the part of the lower garment edge where the cutters first reach their set level. It will be seen that because of this operation waste material falls away from the machine as a strip which can be removed without further ado. This should be contrasted with the unbroken ring of waste material hitherto resulting when mechanical trimming machines were used. These rings, when allowed to accumulate, had to be cut open before they could be removed.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described our invention, we claim as new and desire to secure by Letters Patent:

1. In a garment trimming machine the combination of means to support a garment, cutting means to trim the nether edge of said garment, means to actuate said cutting means, means to revolve said garment supporting means, means to hold said cutting means during cutting in fixed relationship to the axis of revolution of said garment supporting means, means to render said actuating means inoperative, and means to vertically translate said cutting means away from said garment supporting means when said actuating means is rendered inoperative.

2. In a garment trimming machine the combination of means to support a garment, cutting means to trim the nether edge of said garment, means to actuate said cutting means, means to cause relative angular movement of said cutting means about said garment supporting means, and means to move the nether edge of said garment to and past said cutting means at an angular speed substantially equal to the relative angular speed of movement of said cutting means about said garment supporting means.

3. In a garment trimming machine of the character described, in combination means to support a garment, means to revolve said garment supporting means, a cutting station, said cutting station being disposed, when in operative position, in fixed relationship to the axis of revolution of said garment supporting means, means disposed ahead of said cutting station for moving the portion of the garment to be trimmed at an angular speed greater than the angular speed of said garment supporting means whereby to gather up the portions of said garment to be cut, and means disposed substantially at said cutting station to feed said gathered portion of said garment to and past said cutting station at an angular speed substantially equal to the angular speed of said garment supporting means.

4. In a garment trimming machine of the character described, in combination means to support a garment, means to revolve said garment supporting means, a cutting station, said cutting station being disposed, when in operative position, in fixed relationship to the axis of revolution of said garment supporting means, means disposed ahead of said cutting station for moving the portion of the garment to be trimmed at an angular speed greater than the angular speed of said garment supporting means whereby to gather up the portion of said garment to be cut, means disposed substantially at said cutting station to feed said gathered portion of said garment to and past said cutting station at an angular speed substantially equal to the angular speed of said garment supporting means, a control station, and means disposed at said control station to simultaneously render operative or inoperative said means for revolving said garment supporting means, said means for moving said garment and said means for feeding said garment.

5. In a garment trimming machine of the character described, in combination means to support a garment, means to revolve said garment supporting means, a pair of cooperating circular cutter blades, means to revolve said blades in opposite directions, means to hold the axes of revolution of said cutting blades, when said blades are in operative position, in fixed relationship to the axis of revolution of said garment supporting means, and means to reciprocate said blades along their axes of revolution.

6. In a garment trimming machine of the char-

acter described, in combination means to support a garment, means to revolve said garment supporting means, a circular cutting blade, reciprocatable means to shift said blade into a plane of cutting action, and means to cause said blade to revolve as it approaches said cutting plane.

7. In a garment trimming machine of the character described, in combination means to support a garment, a cutting blade, means to cause relative revolution of said cutting blade about said garment supporting means, reciprocatable means to vertically shift said blade into a plane of cutting action, and means to actuate said blade as it approaches said cutting plane.

8. In a garment trimming machine of the character described, in combination a base, a vertically disposed hollow shaft revolvably supported in said base, means to revolve said shaft, a rack gear disposed in and projecting beyond the upper end of said shaft, a pinion meshing with said rack gear and horizontally revolvably supported on said shaft, and means to revolve said pinion.

9. In a garment trimming machine of the character described, in combination means to support a garment, a base, a vertically disposed hollow shaft revolvably supported in said base, means to revolve said shaft, a rack gear disposed in and projecting beyond the upper end of said shaft, a pinion meshing with said rack gear and horizontally revolvably supported on said shaft, a revolvable shaft associated with said pinion, and means to clamp said shaft in any desired angular position, said garment supporting means being movable with said rack gear.

10. In a garment trimming machine of the character described, in combination means to support a garment, a cutting station, means to cause relative revolution of said cutting station about said garment supporting means, a member disposed under said garment supporting means and substantially horizontally aligned with said cutting station, and means cooperating with said member to move portions of said garment to be cut to and past said cutting station at such speed that the said garment is trimmed to a substantially straight edge.

11. In a garment trimming machine of the character described, in combination means to support a garment, a circular member disposed below said garment supporting means, said circular member being of a diameter at least substantially equal to the largest lower dimension of said garment supporting means, means to revolve said garment supporting means and said member, a cutting station disposed in fixed relationship to the axis of revolution of said garment supporting means, means cooperating with said circular member to feed portions of the garment to be trimmed to and past said cutting station at an angular speed substantially equal to the angular speed of said garment supporting means, said means comprising a belt contacting said circular member through portions of the garment being trimmed, means to move said belt at a linear speed substantially equal to the linear speed of movement of the periphery of said circular member, and means to move material to be trimmed to said feeding means, said means comprising a belt spaced away from the periphery of said circular member, and means to move said belt at a linear speed greater than the linear speed of the periphery of said circular member.

SOLOMON SHEER,
VICTOR GINSBURG.
